(57) **CLAIM**

The ornamental design for a table and chair set, as shown and described.

DESCRIPTION

FIG. 1 is a top, front, and right side prospective view of a table and chair set, showing my new design;

FIG. 2 is a top, front, and left side prospective view thereof;

FIG. 3 is a top, front, and left side prospective view thereof;

FIG. 4 is a top, rear, and left side prospective view thereof;

FIG. 5 is a bottom, front, and right side prospective view thereof;

FIG. 6 is a rear elevation view of the Chair from the table and chair set;

FIG. 7 is a front elevation view thereof;

FIG. 8 is a right side elevation view thereof;

FIG. 9 is a left side elevation view thereof;

FIG. 10 is a top plan view thereof;

FIG. 11 is a bottom plan view thereof;

FIG. 12 is a top, rear, and right side prospective view thereof;

FIG. 13 is a top, rear, and left side prospective view thereof;

FIG. 14 is a bottom, rear, and right side prospective view thereof;

FIG. 15 is a bottom, rear, and left side prospective view thereof;

FIG. 16 is a top, front, and left side prospective view thereof;

FIG. 17 is a top, front, and right side prospective view thereof;

FIG. 18 is a bottom, front, and left side prospective view thereof;

FIG. 19 is a bottom, front, and right side prospective view thereof;

FIG. 20 is a front elevation view of the table from the table and chair set;

FIG. 21 is a rear elevation view thereof;

FIG. 22 is a left side elevation view thereof;

FIG. 23 is a right side elevation view thereof;

FIG. 24 is a top plan view thereof;

FIG. 25 is a bottom plan view thereof;

(Continued)

FIG. 26 is a top, front, and left side prospective view thereof;
 FIG. 27 is a top, front, and right side prospective view thereof;
 FIG. 28 is a bottom, front, and left side prospective view thereof;
 FIG. 29 is a bottom, front, and right side prospective view thereof;
 FIG. 30 is a top, rear, and right side prospective view thereof;
 FIG. 31 is a top, rear, and left side prospective view thereof;
 FIG. 32 is a bottom, rear, and right side prospective view thereof;
 FIG. 33 is a bottom, rear, and left side prospective view thereof;
 FIG. 34 is a top, rear, and right side prospective view thereof; and,
 FIG. 35 is a top, rear, and left side prospective view thereof.
